UNITED STATES PATENT OFFICE.

WILLIAM EDMUND MACKENNA, OF BROOKLYN, NEW YORK.

COMPOSITE RUBBER HEEL

1,263,264.

Specification of Letters Patent. Patented Apr. 16, 1918.

Application filed May 5, 1917. Serial No. 166,515.

To all whom it may concern:

Be it known that I, WILLIAM EDMUND MACKENNA, a citizen of the United States, and a resident of the city of New York, 5 borough of Brooklyn, in the county of Kings and State of New York, have invented a new and Improved Composite Rubber Heel, of which the following is a full, clear, and exact description.

10 My invention relates to composite rubber heels, and an object thereof is to provide a detachable rubber heel which has an air cushion.

15 Another object of the invention is to provide a rubber heel in which the air cushion is substantially immune to puncture.

A still further object of the invention is to provide a rubber heel which will present a bulging, yielding wearing surface.

20 I attain the above and other objects of my invention by the structure conventionally disclosed in the accompanying drawings, wherein similar characters of references indicate corresponding parts in all the 25 views.

Figure 1 is a fragmentary side elevation of a shoe provided with a heel embodying my invention;

Fig. 2 is a longitudinal cross section 30 through the heel of the shoe;

Fig. 3 is a transverse section on line 3—3, Fig. 2;

Fig. 4 is a plan view of the composite heel;

35 Fig. 5 is a longitudinal section on line 5—5, Fig. 4; and

Fig. 6 is a perspective view of the composite heel on the plate whereby it may be detachably secured to the permanent heel 40 section of the shoe.

The composite heel 7 has a hardened-rubber border 8 and a flexible or yielding central section 9 which is provided on the inner face of the heel with a spongy-rubber pad 10, the upper surface of which is convex and which bulges mostly near the rear end of the heel 7. This pad 10 may be formed on the heel or cemented thereto.

50 The composite heel may be secured to the permanent heel 11 of the shoe by any suitable means, but preferably the inner face of the composite heel is provided with a recess 12 tapering rearwardly, the sides 13 of which are undercut to engage the raised, flaring sides 14 of a plate 15 which has a taper

similar to the taper of the recess 12. The plate is anchored to the permanent heel 11 of the shoe by prongs 16 raised from the bottom of the plate. The rear end of the plate and the rear end of the recess 12 are preferably rounded to conform to the rounded rear of the heel. The sides 13 of the recess are preferably formed within the border 8 to make the said sides of the recess unyielding to better grip the sides of the plate. 60

When the heel is recessed the pad 10 rises from the recess above the inner face of the composite heel, consequently it will be compressed when the composite heel is forced on to the plate 15. The compression of the 70 pad will force the yielding, central part of the heel to bulge out, thereby presenting a bulging wearing surface, the most of the bulge being near the rear of the heel, due to the fact that the pad originally bulged most 75 near the rear of the composite heel.

The other end of the plate 15 has a lip 17 which comes in contact with the front of the heel and forms an additional stop for the composite heel on the plate, the other 80 stop being formed by the rounded ends of the plate and recess. Preferably an aperture 18 is provided in the plate 15 through which a nail or screw 19 may pass from the composite heel to the permanent heel 11 of 85 the shoe.

As previously pointed out the bulging of the wearing surface is at the rear of the heel and, therefore, at the most advantageous point to relieve the impact caused 90 by walking, as the first point of the shoe coming in contact with the ground is the rear part of the heel. The presence of the spongy rubber between the permanent and composite heel presents an air cushion, 95 which adds to the efficiency of the yielding rubber section and the rubber present in the spongy pad. The air cushion of the spongy rubber in the pad is formed by the air enclosed in the cells of the spongy rubber and, 100 in consequence, the air chamber is substantially immune to puncture, for if some of the cells in the spongy rubber are punctured the efficiency of the other cells will not be impaired. By placing the spongy rubber on 105 the inner surface of the composite heel it is protected by the flexible section 9 from puncture and also from wear. Further, it continuously forces the flexible section 9 outwardly, for as the said section wears its 110

resistance to the pad decreases and, therefore, the pad is able to force the section further as its thickness decreases.

While I have described the principle of operation, together with the device which I now consider to be the best embodiment thereof, I desire to have it understood that the device shown is merely illustrative and that such changes may be made as are within the scope of the appended claims.

I claim:

1. A composite rubber heel having a yielding rubber section and a multicellular air cushion on the inner face of the yielding section bulging the rubber section outwardly.

2. A composite rubber heel having a yielding rubber section and a spongy rubber pad on the inner surface of the yielding section bulging the outer surface of the rubber section.

3. A composite rubber heel having a yielding rubber section and a bulging spongy rubber pad on the inner face of the yielding section, the highest point of said bulging pad being near the rear of the yielding section.

4. A composite rubber heel having a yielding section bordered by a rigid section, and a multicellular air cushion on the inner face of the yielding section.

5. A composite rubber heel having a yielding portion, a rigid portion bordering the yielding portion, and a spongy rubber pad on the inner face of the yielding portion.

40 6. A composite rubber heel having a yielding portion and a rigid portion bordering the yielding portion, a recess in the composite heel, the sides of which recess are formed in the rigid portion, said recess tapering rearwardly and having under-cut sides, a spongy rubber pad in the recess bulging above the face of the yielding portion nearer the rear of the heel, and a plate adapted to engage the recess so as to

force the bulging portion of the pad below the inner surface of the heel, whereby the wearing surface of the heel is bulged out, said plate having means whereby the same 50 may be secured to a permanent heel section of a shoe.

7. A composite rubber heel having a yielding section bordered by a rigid section, said heel having means on the inner surface 55 whereby it may be secured and a multicellular air cushion on the inner face of the heel adapted to be compressed against said inner face when said heel is secured, whereby the yielding section of the heel is caused to 60 bulge out on the wearing surface substantially as and for the purpose set forth.

8. A composite rubber heel having a yielding section, said heel having means on the inner face whereby the heel may be 65 secured, and a bulging, spongy-rubber pad on the yielding section normally projecting above the inner face of the heel, said pad being adapted to be depressed below said inner surface when the heel is secured, 70 whereby the wearing surface of the yielding section is caused to bulge.

9. In combination with a shoe heel, a metal plate secured thereto and presenting outwardly-flaring sides which converge toward the rear of the heel, a composite rubber heel having a yielding section bordered by a rigid section, said composite heel having a recess on the inner face thereof the sides of which are under cut to fit the sides of 75 the plate, said recess converging rearwardly in a manner similar to the plate, and a multicellular air cushion in the recess of the composite heel, said cushion normally bulging above the inner face of the composite 80 heel, whereby said cushion is compressed when said composite heel section is fitted on to the plate, the compression of said air cushion causing the bulging of the wearing surface of the yielding section of the composite heel.

WILLIAM EDMUND MACKENNA.
